CLAIM

The ornamental design for a spraying wand, as shown and described.

DESCRIPTION

FIG. 1 is a side elevational view of a spraying wand embodying my new design;

FIG. 2 is a top plan view of the applicator tip portion thereof;

FIG. 3 is a cross sectional view taken on line 3—3 of FIG. 1;

FIG. 4 is an enlarged front elevational view thereof, with the flexible tubing broken away for convenience of illustration; and

FIG. 5 is a rear elevational view of FIG. 4.

FIG. 4

FIG. 5
